UNITED STATES PATENT OFFICE.

SOLON O. CAMPBELL, OF VAN WERT, IOWA, ASSIGNOR OF ONE-HALF TO
ELIJAH W. CAMPBELL, OF FORT WORTH, TEXAS.

DEVICE FOR CONVERTING MOTION.

SPECIFICATION forming part of Letters Patent No. 279,513, dated June 12, 1883.

Application filed January 29, 1883. (No model.)

To all whom it may concern:

Be it known that I, SOLON O. CAMPBELL, a citizen of the United States, residing at Van Wert Station, in the county of Decatur and

5 State of Iowa, have invented certain new and useful Improvements in Devices for Converting Motion; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to devices for converting motion of the character described in Letters Patent No. 260,452, granted to me July 4, 1882; and it consists in the construction and arrangement of parts, as hereinafter more fully 20 described and claimed.

In the annexed drawings illustrating the invention, Figure 1 is a side elevation of my improved devices for converting motion. Fig. 2 is a side view of the slotted pitman-head and 25 its connections. Fig. 3 is a section on the line $x x$ of Fig. 2, and Fig. 4 represents sectional details of the wrist-block.

Like letters of reference are used to designate the same parts in the several views.

30 Referring to the drawings, it will be seen that the pitman-rods A A are connected by a cross-shaped head or frame, B, having a vertical slot, a , and a horizontal slot, b , said slots intersecting each other centrally, as shown. 35 The rods A A are securely bolted in the ends of the horizontal slot b , and the ends of the vertical slot a are formed by packing-blocks c , that are detachably secured by means of bolts d , for the purpose hereinafter explained. A

40 wrist-block, C, having grooved sides $e e$, is placed in the vertical slot or guideway a of the pitman head or frame B, so as to be capable of reciprocating therein. This wrist-block may be made solid, if desired, but is preferably formed of two grooved plates connected by studs ff , and a perforated central portion, g , on which are formed lateral projecting sleeves or tubular bearings $h h$, as shown in Figs. 3 and 4, the plates $e e$, central connect- 45 ing portion, g , and studs ff being made integral or otherwise. The sleeves $h h$ of the wrist-block C afford a long bearing for the

50 wrist-pin D, which connects the crank-arms E E, that are carried by a transverse shaft, F.

The shaft F and the rods A A are provided 55 with suitable bearings in a frame, G, as shown, or they may be supported in any other suitable manner.

The operation of the device will be readily understood. When power is applied to the 60 shaft F so as to rotate the same, the wrist-block C will be caused to reciprocate within the vertical slot a of the cross-shaped frame B, thus moving the frame from side to side and imparting a reciprocating movement to the 65 rods A A; or, if power is applied to either of the rods A, the shaft F will be caused to rotate.

It will be observed that the transverse slot 70 b of the pitman-head B is of such width as to enable the pitman-head to pass over the shaft F without interference.

It will also be seen that the length of the wrist-block C is such that its advancing end 75 engages in the slot a , above the longitudinal axis of the head B, and passes for a considerable distance therein before its opposite end leaves the slot below it, thus enabling the wrist-block to move with great steadiness and largely diminishing the liability of frictional 80 wear. This advantage will be found to be important.

By detaching the blocks $c c$ at the ends of the vertical slot a and filing or otherwise reducing the ends of said blocks, or by substituting 85 shorter ones therefor, the sides of the vertical slot may be brought closer together, so as to take up any wear of the wrist-block or its guideway.

Having thus described my invention, what I 90 claim as new, and desire to secure by Letters Patent, is—

1. The combination, with the slotted pitman-head B, of the grooved wrist-block C, having sleeves or tubular bearings $h h$ for receiving a wrist-pin, substantially as described. 95

2. The combination of the pitman-rods A A, slotted head or frame B, having detachable blocks $c c$, the wrist-block C, wrist-pin D, cranks E E, and shaft F, substantially as de- 100 scribed.

In testimony whereof I affix my signature in presence of two witnesses.

SOLON OWEN CAMPBELL.
